UNITED STATES PATENT OFFICE.

JOHN B. FRANKE, OF FORT WAYNE, INDIANA, ASSIGNOR TO PERFECTION BISCUIT COMPANY, OF FORT WAYNE, INDIANA, A CORPORATION OF INDIANA.

DISPLAY CONTAINER.

Application filed August 25, 1925. Serial No. 52,285.

This invention relates in general to shipping cartons, and more particularly to that type of shipping carton adapted for use in transporting cakes, crackers and the like, and 5 has for an object, the provision of such a device that may be readily inserted into a display container to display and to identify the contents thereof.

A further object is to provide such a device, 10 the dimensions of which may be reduced from time to time as layer after layer of the contents thereof has been disposed of to bring the remaining contents up to the top, or opening of the display container, and into full 15 view of prospective customers. This is an advantage in that the contents of some containers may be of higher values, or, for other reasons, unless properly displayed, would not be disposed of as readily as the contents of 20 other cartons and, therefore, a display rack may contain many display containers that from all appearances may be empty, as the goods may be too far from the transparent cover to be observed.

25 Numerous other objects and advantages of the invention will be apparent as it is better understood from the following description, which, taken in connection with the accompanying drawings, discloses a preferred embodiment thereof.

Referring to the drawings,

Figure 1 indicates a device embodying my invention;

Fig. 2 is a section taken substantially on 35 line 2-2 of Fig. 1;

Fig. 3 is a perspective view of a cracker caddy embodying my invention; and

Fig. 4 is a view showing the cracker caddy in position in a display container.

40 On the drawings reference character 11 indicates a vertical frame member to which may be secured a plurality of display containers 12 having hinged covers 13, all of which may be of any suitable form or construction. The hinged covers 13 are preferably connected to the container 12 by a hinge pin 14 extending thereacross and engaging suitable guides 15 or the like, and are provided with a transparent or glass front 16.

50 Strips 17 are secured at their opposite ends to two walls of the container and spaced a short distance from another wall thereof as at 18 for supporting a caddy or container 19. The caddy or container 19 is preferably of fibre 55 and may be rectangular, square, or the like, in

cross section and of any suitable height having a plurality of vertical walls 21, 22, 23 and 24, each of these walls having an extension at one end adapted to be bent laterally inward in overlapping relation to form a bottom for the 60 carton, the walls 21 and 23 having at their opposite end a portion 25 adapted to be bent laterally inward and of sufficient length to extend under the transparent front 16 a sufficient distance to display characters indicating the identity and cost of the contents of the 65 carton, and the walls 22 and 24 having a portion 26 of sufficient length and adapted to be bent outwardly and downwardly to adjacent the outer surface of the walls to provide a 70 hook for engaging the strip 17 to support the carton in a display container. Intermediate the ends of the walls 21, 22, 23 and 24, one or more groups of lines or demarcations are 75 printed on the outer surface of the carton indicating lines of severance 27 and lines of bend 28 to facilitate removing one or more portions from the top of the container to reduce the length of the walls 21, 22, 23 and 24.

In operation, crackers or the like are 80 packed in the carton, layer upon layer, from the bottom surface upward and any carton may contain a considerable number of layers. The groups of lines of severance 27 and lines of bend 28 may be printed on the walls of 85 the carton at the line of division of one or more layers, so that as the layers are removed from the carton, it is possible to cut away the top portion or portions of the carton to bring the contents thereof up to adjacent the glass 90 and into full view of a customer as the features at the top of the carton cut away are replaced by severing and bending along the lines indicated and the carton may be reinserted in the display container.

95 It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

100 I claim:

1. A fibre carton, having its walls provided with integral projections disposed at the mouth of the carton, the side walls of said carton having demarcations for indicating lines 110

of severance, whereby said carton may be diminished in size, said lines of severance being constructed and arranged to produce similarly formed projections at the mouth of the 5 carton when diminished in size by severance.

2. A fibre carton, the walls of which are provided with integral, bendable flaps at the mouth of the carton, which flanges are adapted for engagement in a display container for 10 supporting the carton, the walls of said carton being provided with indicating lines of severance, whereby when the carton is cut on such lines of severance its size will be diminished, said lines of severance being constructed 15 and arranged to produce similar formed bendable supporting flaps upon the severance of the carton along such lines.

3. A cracker caddy, comprising, a fibre carton having flanges adapted to be folded back 20 to adjacent an outer surface of the carton and adapted for engagement in a display container for supporting the carton, flanges adapted to extend laterally inward to display characters printed thereon to identify the 25 contents of said container, and means indicating lines of severance for reducing the size of said carton and to produce a similar carton.

4. A shipping carton, comprising a sub-

stantially rectangular fibre container, having two opposed walls at the mouth thereof provided with outwardly bendable integral flaps adapted to engage supporting members for holding the carton in display position, the two opposite walls of said carton having at 30 their mouths integral, inwardly bendable flaps provided with display indicia adapted to be viewed through the transparent cover of a supporting casing when the carton is held in display position, the pairs of opposed walls of said carton being provided with severance lines suitably formed so that when the walls of said carton are cut along said lines the height of the carton will be correspondingly diminished to form at the mouth thereof, 35 pairs of bendable flaps, two to support the diminished container, and two adapted to contain suitable display indicia.

5. In a display device, the combination of an outer sheet metal casing having supporting strips on its inner side wall and spaced intermediate their ends from said wall, a transparent cover for said casing, and a shipping carton having flap parts insertable between said strips and the body walls of the 50 casing to support the carton with its goods displayed through said transparent cover.

JOHN B. FRANKE.
